(57) **CLAIM**

The ornamental design for a wireless charger, as shown and described.

DESCRIPTION

FIG. 1 is a front, top perspective view of a first embodiment of a wireless charger, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is another perspective view of the first embodiment of the wireless charger, shown in an alternative position;

FIG. 10 is another perspective view of the first embodiment of the wireless charger, shown in a position of use;

FIG. 11 is a front, top perspective view of a second embodiment of the wireless charger;

FIG. 12 is a rear, bottom perspective view thereof;

FIG. 13 is a front view thereof;

FIG. 14 is a rear view thereof;

FIG. 15 is a left side view thereof;

FIG. 16 is a right side view thereof;

FIG. 17 is a top view thereof;

FIG. 18 is a bottom view thereof;

FIG. 19 is another perspective view of the second embodiment of the wireless charger, shown in an alternative position;

FIG. 20 is another perspective view of the second embodiment of the wireless charger, shown in a position of use;

FIG. 21 is a front, top perspective view of a third embodiment of the wireless charger;

FIG. 22 is a rear, bottom perspective view thereof;

FIG. 23 is a front view thereof;

FIG. 24 is a rear view thereof;

FIG. 25 is a left side view thereof;

FIG. 26 is a right side view thereof;

FIG. 27 is a top view thereof;

FIG. 28 is a bottom view thereof;

FIG. 29 is another perspective view of the third embodiment of the wireless charger, shown in an alternative position; and,

FIG. 30 is another perspective view of the third embodiment of the wireless charger, shown in a position of use.

The broken lines in the figures illustrate portions of the wireless charger that form no part of the claimed design.

1 Claim, 30 Drawing Sheets
